(57) **CLAIM**

The ornamental design for a side-view mirror cover, as shown and described.

DESCRIPTION

FIG. 1 is a top perspective view of a side-view mirror cover of the present design wrapped around a side-view mirror to show form.

FIG. 2 is a bottom perspective view of the side-view mirror cover of FIG. 1.

FIG. 3 is a front elevation view of the side-view mirror cover of FIG. 1.

FIG. 4 is a back elevation view of the side-view mirror cover of FIG. 1.

FIG. 5 is a side elevation view of the right side of the side-view mirror cover of FIG. 1.

FIG. 6 is a side elevation view of the left side of the side-view mirror cover of FIG. 1.

FIG. 7 is a top plan view of the side-view mirror cover of FIG. 1.

FIG. 8 is a bottom plan view of the side-view mirror cover of FIG. 1.

FIG. 9 is a top perspective view of the side-view mirror cover separated from the side-view mirror of FIG. 1.

FIG. 10 is a top perspective view of the side-view mirror cover of FIG. 1 shown in a loose state free from the side-view mirror; and,

FIG. 11 is a bottom perspective view of the side-view mirror cover of FIG. 10.

In the drawings, the broken lines depict portions of the side-view mirror cover that form no part of the claimed design. The side-view mirror illustrated in the figures is provided to depict environment but does not form part of the claimed design.
